ABSTRACT OF THE DISCLOSURE

A process for making pulp characterized by the step or steps of impregnating comminuted cellulose-containing material with an ammonium compound and an aqueous solution of nitric acid, either sequentially or concurrently, initiating an exothermic oxidation reaction between the lignins of said material and the nitric acid, and controlling the temperature of said material to not exceed about 97° C. until completion of the oxidation reaction.

This application is a continuation in part of my co-pending application, Ser. No. 410,727, filed Nov. 12, 1964, now abandoned.

This invention relates to a process for pulping cellulose-containing material such as hard or soft woods, agricultural straws, vines, stalks and grasses. More particularly, the invention is a process for removing all or any lesser amount of the lignins and other constituents of such material from the cellulose to produce various grades of either high or low yield pulp.

Among the objects of the invention are the following: the employment of nitric acid in minimal amount to achieve the breakdown and/or oxidation of the non-cellulosic constituents of the wood or other raw material, either the employment of a reagent such as ammonium hydroxide in minimal amount in company with the nitric acid or the employment of a wetting agent such as ammonium hydroxide in preceding relation to the use of the nitric acid to both expedite the breakdown and/or oxidation step and to conserve the nitric acid against both direct loss and indirect, or degenerative, loss; and to obtain pulp in such short time and under such process conditions as to time, temperatures, pressures, and amounts of reactants handled and employed as to minimize the expense of pulp production.

One embodiment of the process, which may be carried out on a batch or continuous basis, involves the following steps or their equivalents:

A—The removal of moisture from the raw material, preferably by flushing the raw material, in chip or other comminuted form, with live steam;

B—Contacting the chips with the reactant liquor, an aqueous solution of nitric acid and ammonium hydroxide, in sufficient amount to impregnate the chips;

C—Separating the chips and the excess reactant liquor;

D—Initiating the exothermic oxidation reaction between the lignins and the nitric acid which impregnates the chips, as by subjecting the chips to steam; and

E—Controlling the temperature of the chips to not exceed about 97° C. until the completion of the oxidation

2

reaction while removing from the situs of the chips any gaseous products evolved during the course of the reaction.

Thereafter, the chip material may be hot-washed, steam-softened, caustic-cooked under pressure or not under pressure, cleared of any remaining nitric acid and other chemicals used in the process, final-washed, and beaten or screened, all in general accordance with conventional practices.

The reactant liquor referred to in step B comprises an aqueous solution of nitric acid of about 3° to about 18° Bé. and ammonium hydroxide in a concentration of approximately one part by weight to about 100–250 parts by weight of HNO₃.

The reactant liquor is preferably heated to about 50° C. before being brought into contact with the chips.

Step C may be carried out, for example, by evacuating the liquor on the outside of the chips and by subjecting the chips to a gas pressure on the order of 25 p.s.i. to express excess liquor from within the chips.

The following examples provide data illustrative of the practice of the process of the invention. Pulp of a satisfactory to a very high quality grade was obtained as a result of each of the following process runs.

Example 1 (Redwood)

25	Weight of chips	gr.	607
	Moisture content of chips	percent	12
	Acid strength (15% of 42° Bé.).		
	NH ₄ OH:nitric acid (1 part:100 parts).		
30	Vacuum (28 in.)	min.	8
	Impregnation time	min.	10
	Reaction temperature held at 97° C.	min.	30
	Loss of nitric acid in chips after impregnation (vol.)	ml.	1,000
35	Caustic cook (NaOH conc.)	percent	6
	Cooking time at pressure of 20 lbs.	min.	95
	Beating time	min.	15

Example 2 (Redwood)

40	Weight of chips	gr.	1,140
	Moisture content of chips	percent	36
	Acid strength (15% of 42° Bé.).		
	NH ₄ OH:nitric acid (1 part:100 parts).		
45	Vacuum (28 in.)	min.	10
	Impregnation time	min.	15
	Reaction temperature held at 97° C.	min.	45
	Loss of nitric acid in chips after impregnation (percent)	percent	11
50	Caustic cook (NaOH conc.)	do	7
	Cooking time at pressure of 20 lbs.	min.	100
	After-cook rinse (hot water)	min.	15
	Beating time	min.	15

Example 3 (Rice straw)

55	Weight	lb.	1
	Moisture content	percent	6
	Acid strength (15% of 42° Bé.).		
	NH ₄ OH:nitric acid (1 part:100 parts).		
	Vacuum (28 in.)		
	Impregnation time	min.	10
	Loss of nitric acid in chips	ml.	1,000
60	Reaction time	min.	15
	Reaction temperature	° C.	96
	Hot water wash before caustic cook		None
	Caustic cook		None
65	Beating time	min.	2

Example 4 (Wheat straw)

Weight of straw	gr	1,000
Moisture in straw		Not determined
Acid strength (12% of 42° Bé.).		
NH ₄ OH:nitric acid (1 part:100 parts).		
Vacuum		None
Impregnation time	min	8
Reaction time	min	35
Reaction temperature	° C	94
Caustic cook (NaOH conc.)	percent	5
Cooking time	min	10
Beating time	min	5

Example 5 (Sudan grass)

Weight of grass	gr	650
Moisture of grass		Not determined
Acid strength (12% of 42° Bé.).		
NH ₄ OH:nitric acid (1 part:100 parts).		
Vacuum		None
Impregnation time	min	8
Reaction time	min	30
Reaction temperature	° C	94
Caustic cook (NaOH conc.)	percent	3
Cooking time	min	10
Beating time	min	5

Example 6 (Red fir)

Weight of fir chips	gr	950
Moisture in chips	percent	30
Acid strength (13.5% of 42° Bé.).		
NH ₄ OH:nitric acid (1 part:100 parts).		
Vacuum (28 in.)	min	10
Impregnation time	min	12
Reaction time	min	65
Reaction temperature	° C	96
Caustic cook (NaOH conc.)	percent	6
Cooking time	min	40
Beating time	min	10

Example 7 (Bagasse)

Weight of bagasse	gr	730
Moisture in bagasse		Not determined
Acid strength (13% of 42° Bé.).		
NH ₄ OH:nitric acid (1 part:100 parts).		
Vacuum		None
Impregnation time	min	8
Reaction time	min	40
Reaction temperature	° C	94
Caustic cook (NaOH conc.)	percent	5
Cooking time	min	20
Beating time	min	10

Example 8 (Alder)

Weight of chips	gr	875
Moisture in chips	percent	15
Acid strength (12% of 42° Bé.).		
NH ₄ OH:nitric acid (1 part:100 parts).		
Vacuum (28 in.)	min	10
Impregnation time	min	12
Reaction time	min	35
Reaction temperature	° C	94
Caustic cook (NaOH conc.)	percent	5
Cooking time	min	25
Beating time	min	12

Example 9 (Pine)

Weight of chips	gr	1020
Moisture in chips	percent	25
Acid strength (13.5% of 42° Bé.).		
NH ₄ OH:nitric acid (1 part:100 parts).		
Vacuum (28 in.)	min	10
Impregnation time	min	10
Reaction time	min	70
Reaction temperature	° C	94
Caustic cook (NaOH conc.)	percent	5
Cooking time	min	30
Beating time	min	15

Example 10 (Tamerack)

Weight of chips (approx.)	gr	1,000
Moisture in chips		Not determined
Acid strength (13.5% of 42° Bé.).		
NH ₄ OH:nitric acid (1 part:100 parts).		
Vacuum (28 in.)	min	7
Impregnation time	min	12
Reaction time	min	65
Reaction temperature	° C	96
Caustic cook (NaOH conc.)	percent	13
Cooking time	min	60

Example 11 (Aspen)

Weight of chips	lbs	100
Moisture in chips	percent	50
Acid strength (15% of 42° Bé.).		
NH ₄ OH:nitric acid (1 part:100 parts).		
Vacuum (28 in.)	min	5
Impregnation time	min	13
Reaction time	min	60
Reaction temperature	° C	96
Caustic cook (NaOH conc.)	percent	5
Cooking time	min	50
Cooking pressure	p.s.i.	10
Beating time	min	15

Example 12 (Rice straw)

Weight of straw	lbs	20
Moisture in straw	percent	10
Acid strength (3.5% of 42° Bé.).		
Vacuum (28 in.).		
Impregnation time	min	10
Reaction time	min	20
Reaction temperature	° C	96
Caustic cook (NaOH conc.)	percent	2
Cooking time	min	15
Cooking pressure	p.s.i.	10
Beating time	min	10

Example 13 (White spruce)

Weight of chips	lbs	110
Moisture in chips	percent	50
Acid strength (15% of 42° Bé.).		
Tw. of acid	degrees	90
NH ₄ OH:nitric acid (1 part:100 parts).		
Vacuum (28 in.).		
Impregnation time	min	15
Reaction time	min	60
Reaction temperature	° C	96
Caustic cook (NaOH conc.)	percent	6
Cooking time	min	70
Cooking pressure	p.s.i.	10
Beating time	min	20

A further and preferred embodiment of the process, which may be carried out on a batch or continuous basis, involves the following steps or their equivalents:

A—The impregnation of the raw material, in chip or other comminuted form, with ammonium hydroxide, or the equivalent thereof as a wetting or leaching agent for said raw material, followed by the expressing of the impregnant from said raw material;

B—Impregnating the raw material with an aqueous solution of nitric acid;

C—Separating the raw material and the excess nitric acid;

D—Initiating the exothermic oxidation reaction between the lignins and the nitric acid which impregnates the raw material, as by subjecting the latter to steam; and

E—Controlling the temperature of the raw material to not exceed about 97° C. until the completion of the oxidation reaction while removing from the situs of the raw

material any gaseous products evolved during the course of the reaction.

This preferred embodiment of the process is particularly advantageous for use where the raw material is a vegetable material.

Before subjecting the vegetable material to the action of ammonium hydroxide, the material is cut into small pieces approximately 1 inch in length. The material is then preferably steamed, thereby allowing for faster impregnation of the material by the ammonium hydroxide which serves to nitrate the lignins in the raw material.

The steamed raw material is then immersed into a hot (preferably within the range of about 45-60° C.) solution of 8% ammonium hydroxide at atmospheric pressure. Time required to dis-incrust the raw material depends on whether it is a low or high density material, such time being usually within the range of about 30 to about 60 minutes. When the material has become impregnated with the ammonium hydroxide, it is subjected to a press, for example, to remove all of the excess ammonium hydroxide. The remaining ammonium hydroxide within the raw material is approximately 2% by weight thereof.

The vegetable material is then impregnated with an aqueous solution of nitric acid having a concentration of from about 8% to about 20% of 44° Baume, the solution of nitric acid having been brought to a temperature of not in excess of about 45° C. The impregnation time is from about 8 to about 15 minutes depending upon the density of the particular raw material being used. The impregnation time can of course be reduced if pressure is employed during this step. The vegetable material will absorb from about 20% to about 32% by weight of the nitric acid solution depending upon the moisture content of the raw material.

The use of the ammonium hydroxide in the manner described results in a shorter reaction time for the subsequent oxidation reaction with nitric acid and enables a minimum usage of nitric acid from the standpoint of the amount required for the oxidation reaction. As a result of the oxidation reaction time being shortened and the decreased usage of nitric acid, pulp cannot only be produced at a lower cost per ton but with a lesser chance of hydrolysis occurring.

The loss of nitric acid solution due to such solution remaining in the vegetable material varies slightly with various raw materials, amounting to from about 20% to about 32% by weight of the vegetable material.

After the ammonium hydroxide is expressed from the vegetable material, the ammonium hydroxide remaining in this material acts as a wetting agent, thereby speeding up the rate of penetration of the nitric acid solution into the raw material.

Some examples of the preferred embodiment of the subject process are as follows:

Example 14 (Wheat straw)

Weight of wheat straw	gr	700
Moisture content of straw	percent	1
Wheat straw steamed then immersed in hot solution of NH ₄ OH, 6% of 26° Baumé	min	30
All but approximately 2% of the NH ₄ OH then pressed from the wheat straw.		
Nitric acid aqueous solution brought to a temperature of 45° C.		
Straw impregnated with hot nitric solution of 12% of 42°	min	10
Loss of nitric acid in impregnation	ml	550
Reaction temperature held at 94° C.	min	30
Caustic cook (NaOH)	percent	3
Cooking time at pressure of 20 lbs.	min	15
Beating time	min	1
Hot water wash.		
Screen.		
Yield, approximately	percent	37 75

Example 15 (Maize stalk)

Weight of maize stalk	gr	750
Moisture content of maize	percent	2
Maize steamed then immersed in hot solution of NH ₄ OH, 8% of 26° Baumé	min	35
All but approximately 2% of the NH ₄ OH then pressed from the maize stalk.		
Nitric acid aqueous solution brought to a temperature of 45° C.		
Maize impregnated with hot nitric solution of 15% of 42° Baumé	min	12
Loss of nitric acid in impregnation	ml	600
Reaction temperature held at 96° C.	min	35
Caustic cook (NaOH)	percent	4
Cooking time at pressure of 20 lbs.	min	20
Beating time	min	2
Hot water wash.		
Screen.		
Yield (approximately)	percent	35

Example 16 (Cotton stalk)

Weight of cotton stalk	gr	800
Moisture content of cotton stalk	percent	2
Cotton stalk steamed then immersed in hot solution of NH ₄ OH, 5% of 26° Baumé	min	45
All but approximately 2% of the NH ₄ OH then pressed from the cotton stalk.		
Nitric acid aqueous solution brought to a temperature of 45° C.		
Cotton stalk impregnated with hot nitric solution of 15% of 42° Baumé	min	12
Loss of nitric acid in impregnation	ml	525
Reaction temperature held at 96° C.	min	35
Caustic cook (NaOH)	percent	3
Cooking time at 20 lbs. pressure	min	20
Beating time	min	2
Hot water wash.		
Screen.		
Yield (approximately)	percent	37

Example 17 (Maize stalk)

Weight of maize	gr	825
Moisture content of maize	percent	2
Maize steamed then immersed in a hot solution of NH ₄ OH, 10% of 26° Baumé	min	60
All but approximately 2% of the NH ₄ OH then pressed from the maize stalk.		
Nitric acid aqueous solution brought to a temperature of 45 C.		
Maize impregnated with hot nitric solution of 20% of 42° Baumé	min	15
Loss of nitric acid in impregnation	ml	650
Reaction temperature held at 95° C.	min	40
Caustic cook (NaOH)	percent	5
Cooking time at pressure of 20 lbs.	min	20
Beating time	min	3
Hot water wash.		
Screen.		
Yield (approximately)	percent	38

What is claimed is:

1. In the process for making pulp comprising cellulose from a raw material selected from the classes consisting of wood and vegetable matter in sub-divided form, the breaking down of lignins in the raw material by:

- presteaming the raw material to decrease the moisture content of the raw material to thereby increase the capacity of the raw material to become impregnated with an aqueous solution;
- impregnating the raw material with a dilute aqueous solution of nitric acid which also contains as a solute an amount of ammonium hydroxide, the ammonium hydroxide having a concentration of about

- one part by weight for about every 100-250 parts by weight of HNO_3 present in said solution;
- (C) removing the excess of said solution from the raw material;
- (D) heating the raw material to initiate an exothermic reaction between the HNO_3 impregnant of the raw material and lignins of the raw material; and
- (E) controlling the temperature of the raw material during the reaction so that it does not exceed about 97° C.
2. In the process for making pulp comprising cellulose from a raw material selected from the classes consisting of wood and vegetable matter in sub-divided form, the breaking down of lignins in the raw material by:
- (A) impregnating the raw material with a dilute aqueous solution of nitric acid which also contains as a solute an amount of ammonium hydroxide, the ammonium hydroxide having a concentration of about one part by weight for about every 100-250 parts by weight HNO_3 present in said solution;
- (B) removing the excess of said solution from the raw material;
- (C) heating the raw material to initiate an exothermic reaction between the HNO_3 impregnant of the raw material and lignins of the raw material; and
- (D) controlling the temperature of the raw material during the reaction so that it does not exceed about 97° C.
3. In the process for making pulp comprising cellulose from a raw material selected from the classes consisting of wood and vegetable matter in sub-divided form, the breaking down of lignins in the raw material by:
- (A) impregnating the raw material with a dilute aqueous solution of ammonium hydroxide and removing the excess of said ammonium hydroxide from said raw material;
- (B) impregnating the raw material with a dilute aqueous solution of nitric acid and removing the excess of said nitric acid from said raw material;
- (C) heating the raw material to initiate an exothermic reaction between the HNO_3 impregnant of the raw material and lignins of the raw material; and then

- (D) controlling the temperature of the raw material during the reaction so that it does not exceed about 97° C.
4. In the process for making pulp comprising cellulose from a raw material selected from the classes consisting of wood and vegetable matter in sub-divided form, the breaking down of lignins in the raw material by:
- (A) impregnating the raw material with a dilute aqueous solution of ammonium hydroxide and removing the excess of said ammonium hydroxide from said raw material;
- (B) impregnating the raw material with a dilute aqueous solution of nitric acid and removing the excess of said nitric acid from said raw material;
- (C) heating the raw material to initiate an exothermic reaction between the HNO_3 impregnant of the raw material and lignins of the raw material, said solution of ammonium hydroxide having a temperature during impregnation within the range of about 45-60° C., and said solution of nitric acid having a temperature during impregnation and prior to said exothermic reaction of about 45° C.; and then
- (D) controlling the temperature of the raw material during the reaction so that it does not exceed about 97° C.
